SPRING FOR FRUIT AND FLOWER CUTTERS

Therl C. Lynch, Kelseyville, Calif.

Application September 6, 1935, Serial No. 39,489

1 Claim. (Cl. 30—24)

This invention relates to an improved spring for fruit and flower cutters or clippers, the general object of the invention being to provide a spring of great strength and including a coil and arms with means for anchoring one arm to one of the members of the cutter, the other arm having sliding movement on the other member.

This invention also consists in certain other features of construction and in the combination and arrangement of several parts, to be herein-after fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is an elevation showing the improved spring attached to a clipper or cutter.

Figure 2 is a section on the line 2—2 of Figure 1. Figure 3 is a plan view of the spring itself.

As shown in the drawing, I provide a spring A which consists of the coiled part 1 and the arms 2 and 3. The coiled part 1 is placed on the inner edge of one of the members B of the clipper or cutter C with the arm 2 clamped to a side edge of the member B by a clamp 4 and with the hook-shaped ends 5 of the arm 2 fitting in a recess 6 in the inner edge of the member B. The other arm 3 is bent at substantially right angles as shown at 7 and slides on the inner edge of the member B'.

Thus it will be seen that the arm 2 and the coiled part 1 are held on the member B while the other arm has its part 7 pressing against the member

B' so as to hold the cutter with the jaws separated and during movement of the handles of the cutter this part 7 will slide on the part B' so that the spring will hold the cutter open with but little strain on the spring.

This spring will last a long time whereas the usual springs used with devices of this type often break one or more times each day, this spring fitting in the recesses formed in the handle parts and which is shown in Figure 2.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

A spring attachment for clippers of the pivotal handles type comprising a split clamp band for encompassing one handle of a clipper and having a screw whereby the ends of the band may be brought together for snugly holding the band around the handle, said band being provided with a transverse corrugation, a coiled spring having a pair of leg extensions, one of said leg extensions being provided with a laterally disposed portion for engaging the inner side of one handle, the other leg of the spring being disposed through the corrugation of the clamp and being provided at its free end with a hook for engaging over the corresponding handle.
